CLAIM

The ornamental design for drinking container, as shown and described.

DESCRIPTION

FIG. 1 is a top, front, right side perspective view of the drinking container showing our new design;

FIG. 2 is a top, back, left side view perspective thereof;

FIG. 3 bottom, front, right side view perspective thereof;

FIG. 4 bottom, rear, left side view perspective thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

Features shown in dashed line form no part of the claimed invention. Portions of the lid above the dot-dash boundary line around the outer circumference of the cartridge receiving cavity of the lid and visible in FIGS. 3-8 and 10 form no part of the claimed design.

1 Claim, 10 Drawing Sheets
